SKI EDGE

Henry Hohmann, Brooklyn, N. Y.

Application February 12, 1943, Serial No. 475,691

5 Claims. (Cl. 280—11.13)

This invention relates to new and useful improvements in metal runners for skis, and relates more particularly to an improved means of forming the meeting terminals of the several abutting strips secured along each marginal edge of the lower surface of a ski.

It is well known that skis formed with metal edges or runners are much more satisfactory from the standpoint of performance than are skis wherein the entire running surface is formed of wood. The metal runner protects the edges against chipping due to contact with stones and other hard objects, and greatly increases the effective life of the skis. In accordance with the usual practice, the opposed marginal edges of the running surface of the ski are recessed, and a metal edging is positioned within such recess, the lower surface of the edging being substantially plane with the lower or running surface of the ski, and likewise the outer marginal edge of the edging being substantially flush with the vertical edge of the ski.

During normal skiing operations, particularly when making sharp turns and performing other difficult feats, the ski frequently flexes considerably; that is to say, the lower or running surface forms a convex arc, and accordingly if the metal runner on each side of the ski were made in one continuous piece, such a great strain would be imposed upon the strip as to cause it to be pulled away from its supporting screws. Also, the provision of a single length of metal edging on each side of the ski running substantially the full length thereof and secured at intervals of six or eight inches to the ski by means of counter-sunk screws, would greatly reduce the normal and highly desired flexibility of the wooden ski. Another objection to the continuous runner resides in the fact that the metal and the wood have a different coefficient of expansion and contraction, and accordingly the screws or other securing means would be under constant strain almost all the time.

To remove these objections, the metal runner has generally been formed in abutting, discontinuous sections, the meeting terminals usually being provided with various kinds of complementary tongue-and-groove portions rather than having flat, abutting ends. In all of the devices of the art, however, there has been a tendency for these terminal portions to be picked up by stones or other hard material encountered in the course of skiing, with the result that these terminals are bent downwardly, thus greatly impeding the possible speed of the ski. When these ter-

minal portions have been displaced, there is also great danger of injury to the skier, and accordingly the principal object of the present invention is to provide a novel interlocking construction of the meeting terminal portions of the several sections wherein it is virtually impossible for these terminal sections to be separated from the ski itself.

In the ordinary devices of the art, there is somewhat less danger of transverse shifting of the abutting terminals than there is for such terminals to lift from the surface of the rabbet, for the reason that the usual dovetail or tongue-and-groove arrangement prevents the former, although it does not prevent the lifting. In accordance with the present invention, lifting of one or the other of the terminals is definitely prevented by a novel interlocking arrangement including a plurality of pairs of bevelled, cooperating surfaces, one pair being bevelled in one direction, and another in a different direction. The arrangement permits free flexing of the ski wherein the meeting terminals of the sections may move away from each other a slight distance in a telescopic fashion, without, however, causing these tongue-and-groove terminals to become disengaged. This is of the greatest importance, primarily for the reason that in the older devices the ski on occasions flexes so greatly as to cause the tongue to completely leave the groove, and then be so dislocated as to be unable to re-enter the groove. In accordance with the present invention, however, the continuous smooth surface of the runner sections cannot be disturbed, regardless of the strain or flexing of the skis.

In the drawing:

Fig. 1 is a broken bottom plan view of a ski embodying the present invention.

Fig. 2 is a transverse section taken on line 2—2 of Fig. 1.

Fig. 3 is an enlarged bottom plan view of the complementary meeting terminal sections of the runners forming one embodiment of the present invention, such terminals being shown in spaced relation.

Fig. 4 is similar to Fig. 3, but shows the terminal sections in assembled relation.

Fig. 5 is a broken longitudinal section taken on line 5—5 of Fig. 4.

Fig. 6 is an enlarged longitudinal section taken on line 6—6 of Fig. 4.

Fig. 7 is a perspective view of the meeting terminal sections in spaced relation and showing the upper surface thereof.

Fig. 8 is a bottom plan view of the meeting terminal sections of metal runners forming a modified embodiment of the invention.

Fig. 9 is a side elevation of the structure shown in Fig. 8.

Fig. 10 is a perspective view thereof.

Fig. 11 is a broken plan view of another form of the invention, the complementary meeting edges being shown in spaced relation.

Fig. 12 is a section taken on line 12-12 of Fig. 11 with the parts in assembled relation.

Fig. 13 is a similar section taken on line 13-13 of Fig. 11.

Fig. 14 is a perspective view showing this form of the invention.

The ski proper is shown at 15 and may be of the usual construction, and may have the cross-sectional contour shown particularly in Fig. 2. The lower surface is flat, and there is formed along each marginal edge of such lower surface a longitudinal recess or rabbet 16 which receives the sectional metal runners 17. The particular cross-sectional dimensions of the runners are, of course, a matter of choice. The width of the recess, however, should be such as to cause the outer marginal edge of the runner to be flush, or substantially flush, with the vertical side edge of the ski, and in depth should also be such as to cause the lower surface of the runner to be flush with the lower surface of the ski, all as is well known in the art. The recesses may run substantially the full length of the ski, and may, if desired, terminate at a point spaced from the rear end of the ski.

In accordance with usual practice, the runners are not formed of a single, continuous length on each side of the ski, but rather are formed in sections, each of such sections being secured to the ski by means of flat-headed screws 18 received in apertures 19 which are counter-sunk in order to permit the flat head of the screw to be substantially flush with the lower surface of the runner or to lie slightly inside the running surface. The formation of the complementary terminal portions of each adjacent set of runners is such as to prevent the movement of any portion of the runner transversely of the ski as well as vertically thereof. In other words, if the runners were to shift transversely of the ski, or its terminals were to be picked up from the surface of the recess, the result would be a projecting member that would impede movement of the ski and might result in injury to the skier.

The first form of the invention is illustrated particularly in Figs. 3 to 7, inclusive, and includes a plurality of the sections, each provided at opposite ends thereof with complementary tongue-and-groove terminals 22 and 23, respectively. Referring to tongue terminal 22, the upper surface of tongue 24 is flush with the upper surface 25 of the runner. The lower surface 26 of the tongue is bevelled, and on each side of the tongue are oppositely bevelled surfaces 27. In the groove terminal 23, the groove 30 is of such width as to receive the tongue with a fairly snug fit, and the inner terminal of the groove is bevelled, as shown at 31, such bevelled surface being on the same plane as lower surface 26 of the tongue. Side portions or extensions 32 and 33 defining the groove are bevelled on their lower surfaces 34. Bevelled surfaces 27 on the tongue terminal lie on the same plane as do bevelled surfaces 34 on extensions 32 and 33.

It will accordingly be seen that as the tongue terminal is moved into interlocking engagement with the groove terminal, the lower surface 26 of the tongue engages upper surface 31 of the groove, and thus downward movement of the tongue relative to the groove is definitely prevented. Likewise, upper bevelled surfaces 27 of the tongue terminal engage the lower surfaces 34 of extensions 32 and 33, thus preventing downward movement of groove terminal 23 relative to tongue terminal 22. It will likewise be apparent that lateral movement of either terminal relative to the other is definitely not permitted due to the tongue-and-groove formation. Inasmuch as the outer end of the tongue is not exposed when the several sections are secured to the ski, such edge may be sharp, if desired, although the outer edges of surfaces 27 and surface 31 are preferably somewhat flattened, as shown at 37 and 38, respectively, in order to avoid an exposed knife edge on the lower or running surface of the sections. In the arrangement shown, the tongue terminal is positioned at the rear of each section, although this may, if desired, be reversed.

In the modified arrangement shown in Figs. 8, 9 and 10, the individual runner sections are provided with complementary terminals 40 and 41, terminal 40 having on its upper surface 42 a bevelled surface 43 extending substantially half the width of the runner. On the opposite side of the runner the lower surface is provided with a bevelled surface 44. Upper bevelled surface 43 engages a lower bevelled surface 45 in terminal 41, and lower bevelled surface 44 of terminal 40 cooperates with an upper bevelled surface 45 in terminal 41. This ingenious arrangement also prevents lateral shifting of one strip relative to the other, and likewise definitely prevents either terminal section from lifting from the lower surface of the ski. Likewise, in this instance, the outer terminals of the bevelled surfaces are desirably somewhat flattened in order to avoid knife edges on the lower surface of the ski.

Another form of the invention is illustrated in Figs. 11 to 14, inclusive. In this instance, the bevelled surfaces are eliminated entirely, although the tongue-and-groove aspect of the first embodiment is preserved. Terminal 50 has a tongue 51 which is half the thickness of the runner. On each side of the tongue, recesses 52 and 53 are provided, the material below such recesses likewise being half the thickness of the runner. The groove 54 extends rearwardly to wall 55, and this groove is likewise half the thickness of terminal 56. Extensions 57 are received in recesses 52 in terminal 50. It will be appreciated that the surface shown in Fig. 11 may be either the upper or the lower surface of the runner.

The runners of the present invention are desirably made from steel or other metal because of its hardness and resistance to wear. The invention is by no means limited to the use of metal, however, particularly since various plastics and other materials may serve well for the purpose. Also, it must be appreciated that the several embodiments of the invention described and illustrated herein are offered for the purpose of illustration only, and are not to be taken in any limiting sense. In other words, many other forms may be utilized without departing from the spirit of the invention as defined by the appended claims.

What I claim is:

1. A metal runner for a ski or the like, such runner being formed in a plurality of discontinuous abutting sections formed with tongue-and-groove, slightly overlapping terminals, the lower surface of the tongue and the upper surface of the inner end of the groove being bevelled on substantially the same angle to permit the two surfaces to contact one another, the lower surfaces of the groove terminal and the adjacent surfaces of the tongue terminal being oppositely bevelled, thus providing an interlocking tongue-and-groove joint.

2. A ski runner formed in a plurality of discontinuous, abutting sections provided with complementary tongue-and-groove terminal portions, the tongue portion including a centrally disposed tongue whose upper surface is substantially plane with the upper surface of the runner, and whose lower surface is bevelled with its greatest thickness at its inner end, the upper terminal surfaces on opposite sides of the tongue being bevelled oppositely from the bevel on the lower surface of the tongue, the groove terminal having a groove therein formed at its inner end with a bevelled surface complementary to the bevelled surface of the tongue and receives such latter bevelled surface in substantial meeting engagement, the lower terminal surfaces of the groove terminal being bevelled complementary to the bevelled upper surfaces of the tongue terminal, such complementary surfaces being in substantial meeting engagement.

3. A ski formed with recesses along the marginal edges of the running surface, and a runner secured in each recess, each runner formed in a plurality of abutting sections provided with opposed, complementary tongue-and-groove termi-

nals, the tongue terminal including a centrally disposed, projecting tongue whose upper surface is substantially plane with the upper surface of the runner, and whose lower surface is bevelled with its greatest thickness at its inner end, the upper terminal surfaces on each side of the tongue being bevelled with their greatest thickness at their inner ends, the groove terminal being bifurcated to provide a groove formed at its inner end with a bevelled surface to receive in surface engagement the lower bevelled surface of the tongue, the lower surfaces of the bifurcated terminals being bevelled to receive the upper bevelled surfaces of the tongue terminal.

4. A ski having a recess along a marginal edge of the running surface, and a runner secured in such recess and formed of a plurality of discontinuous, abutting sections provided at their meeting terminals with complementary tongue-and-groove joints, the lower surface of the tongue being bevelled, and the groove having, at its inner end, a complementary bevelled upper surface to receive the tongue, the lower surface of the groove terminals being oppositely bevelled, and the upper surfaces of the tongue terminal on each side of the tongue being bevelled to receive the bevelled surfaces of the groove terminals.

5. A metallic runner for a ski or the like, such runner being formed in a plurality of abutting, slightly overlapping sections formed with complementary tongue-and-groove terminals, the lower surface of the tongue being bevelled and the upper surfaces of the portions lying on each side of the tongue being oppositely bevelled, the groove terminal having complementary bevelled surfaces to receive the bevelled surfaces of the tongue terminal.

HENRY HOHMANN.
